UNITED STATES PATENT OFFICE.

BERTRAM J. GOLDSMITH, OF NEW YORK, N. Y., ASSIGNOR, BY MESNE ASSIGNMENTS, TO PERFECT WINDOW REGULATOR CORPORATION, OF LONG ISLAND CITY, NEW YORK, A CORPORATION OF DELAWARE.

WINDOW-COUNTERBALANCING DEVICE.

Application filed July 26, 1924. Serial No. 728,310.

My invention relates to windows of the type which are slidable vertically.

The invention has for its principal object the production of a novel guideway within which the window is supported and on which the window is slidable, said guideway being of simple construction and acting to prevent the window from rattling.

A further object of the invention is the production of a guideway of the type specified which shall also have the function of urging the window upwardly and acting as a counterbalance therefor.

With the above and other objects in view the invention consists in the novel device hereinafter described and then specified in the claims.

In the accompanying drawing showing a practical embodiment of the invention:

20 Fig. 1 is a front elevation of a window frame and window.

Fig. 2 is an enlarged section taken through one of the side members of the frame.

25 Fig. 3 is a transverse section taken through one of the side members and a part of the window.

Fig. 4 is a view similar to Fig. 3 but showing a slight modification.

Referring in detail to the several figures 30 of the drawing:

1 indicates the side members of a window frame, while 2 and 3 indicate the upper and lower members thereof. Said side members are each provided with a channel 4. The 35 window itself which may be either a framed or frameless pane is indicated at 5 and is provided at the lower edge thereof with a U-strip 6 in which the window is seated and to which it is secured in any manner, said strip also having fastened thereto a downwardly depending slotted plate 7. The U-shaped strip 6 is provided with an extension 8 at either end projecting within the channels 4.

45 9 indicates a supporting plate or board extending across the window and fastened to the side members 1 and which in reality constitutes a wall of the window well into which the window is slidable. Mounted on 50 said plate or board is a rotatable crank or handle 10 the shaft of which carries a pinion or gear (not shown) meshing with a toothed segment 11 fastened to or forming a part of a pivoted operating arm 12, the end of

which is provided with a roller 13 engaging 55 within the slot of the plate 7.

In each of the channels 4, I locate a long squared spiral spring 14 the outer side of which is inwardly rounded or depressed as indicated at 15. The upper ends of said 60 springs are secured to the upper wall of said channels while the lower ends are fastened to the extensions 8 of the U-strip 6. The sides of the window 5 slidably engage within the rounded or depressed portion 15 65 of said springs. Said springs therefore, not only provide supporting guideways for the window but inasmuch as they are fastened thereto in the manner described they are constantly exerting an upward effort on the 70 window and in consequence assist in the raising thereof. Furthermore they prevent the window from rattling irrespective of its position.

The window may be raised and lowered 75 by rotation of the crank or handle 10 whereby the operating arm 12 is caused to swing on its pivot, the roller 13 then sliding the slot of the plate 7 and forcing the window upwardly or downwardly depending on the 80 direction of rotation given the crank or handle. This operating mechanism per se is old in the art, however, and forms no part of the present invention.

In the modification illustrated in Fig. 4 85 the ends of the channels are bent inwardly toward the window as indicated at 16 this acting to prevent the springs from becoming dislodged from their proper position.

What I claim as my invention is:

1. In a window, a guideway therefor in which the window is vertically slidable, said guideway being adapted to exert an upward effort on said window.

2. In a window, a guideway therefor comprising a spiral spring on which the window is vertically slidable, said guideway acting to exert an upward effort on said window.

3. In a window, a guideway therefor engaging the side of the window and in which the window is vertically slidable, said guideway acting to counterbalance the weight of the window.

4. In a window, means for raising and lowering the same and a guideway receiving the side edge of the window and acting to assist in the raising operation thereof.

5. In a window, a U-shaped channel, a

- spring in said U-shaped channel engaging the window and on which said window is slideable, said spring acting also to assist in the raising of the window.
6. In a window, a guideway therefor comprising a squared spiral spring having a rounded portion receiving the side of the window and in which said window is slideable.
10. 7. In a window, a U-shaped channel and a spring therein fastened to said channel and to the window, said window being slideable on said spring.
8. In a window, a channel, a window having an extension extending within said channel and a spring fastened to said channel and to said extension and on which the window is slideable vertically.
9. In a window, a U-shaped channel, a spring therein fastened to the window and to said channel and on which said window is slideable, said channel having its free ends turned inwardly towards the window.
10. In a window, a guideway therefor in which the window is vertically slideable, said guideway being adapted to exert an upward effort on said window and means for raising and lowering said window.
11. In a window, a U-shaped channel in which the window is vertically slideable, a U-shaped strip fastened to the lower edge of the window and a spring in said channel fastened thereto and to said strip and exerting an upward effort on said window.
12. In a window, a window frame provided with U-shaped channels therein in which the window is slideable, a U-shaped strip fastened to the lower edge of the window, a spring in said channel fastened to the upper end thereof and to said strip and exerting an upward effort on said window.

Signed at New York in the county of New York and State of New York this 25th day of July A. D. 1924.

BERTRAM J. GOLDSMITH.
